UNITED STATES PATENT OFFICE.

LEONARD F. FULLER, OF PALO ALTO, CALIFORNIA, ASSIGNOR, BY MESNE ASSIGNMENTS, TO WIRELESS IMPROVEMENT COMPANY, OF JERSEY CITY, NEW JERSEY, A CORPORATION OF NEW JERSEY.

SIGNALING SYSTEM.

Application filed June 13, 1922. Serial No. 568,074.

To all whom it may concern:

Be it known that I, LEONARD F. FULLER, a citizen of the United States, residing at 1499 Cowper St., Palo Alto, in the county of Santa Clara, State of California, have invented certain new and useful Improvements in Signaling Systems; and I do hereby declare the following to be a full, clear, and exact description of the invention, such as will enable others skilled in the art to which it appertains to make and use the same.

This invention has for its object the provision of an arc signaling system in which auxiliary means are employed for establishing and maintaining the arc under conditions where it could ordinarily neither establish itself nor maintain itself after having been established by any of the well known methods; and further, the utilization of such an arrangement for signaling with arc converters of all sizes and powers.

In accordance with the invention an arc of any size or power may be established and maintained or extinguished at will for signaling purposes by means of an auxiliary circuit separate and distinct from the main circuit which supplies current to the arc, the auxiliary circuit being controlled by the manipulation of a sending key or a high speed automatic sender or the like. In this way the usual difficulties encountered in interrupting, varying, or otherwise directly controlling the current supplied to the arc electrodes are overcome. Further, since the arc is started and stopped for each dot and dash or other character, it is possible to save the power ordinarily consumed between dots and dashes, words, messages, etc.; and the power so saved may, in many cases, amount to more in kilowatt-hours than the power actually consumed during the transmission of messages. Moreover, an arc transmitter in which such an arrangement is embodied becomes inherently uni-wave in operation since the arc is actually started and stopped in accordance with the conventional signaling characters, energy being radiated at but a single wave length—that of the signal.

In U. S. Letters Patent Nos. 1,316,172 and 1,844,052, granted to R. G. Marx and myself, and No. 1,339,191, granted to myself, there is disclosed various methods of signal-

ing with an arc transmitter wherein an auxiliary circuit is employed to furnish a discharge across the arc electrodes for the sole purpose or reigniting the arc. None of these arrangements, however, utilize the reignition discharge for the purpose of maintaining the arc for signaling purposes, since in each of the arrangements the arc will continue to burn and maintain itself unaided by the discharge after having been once ignited.

A joint application of George C. Sweet and myself, filed March 16, 1921, Serial No. 452,789, discloses a uni-wave arc signaling system employing an arc fed by alternating current and having a varying electro-magnetic field. This system utilizes a stable alternating current arc, that is, the arc when once ignited will continue to burn; and signaling is accomplished by interrupting or otherwise directly controlling the current supplied to the arc electrodes in accordance with the usual conventional characters. The alternating current arc therein described may however, be arranged to automatically ignite itself by employing suitably spaced arc electrodes and a proper value of applied potential. To provide against contingencies however, and other conditions tending to produce irregular operation, certain stabilizing systems are described in that application, by means of which the arc may be reignited and thus stabilized in the course of its operation. Those systems are, however, designed only for stabilizing the arc and are not adapted to be used for signaling purposes.

The present invention involves, as distinguished from the arrangements described in the aforementioned U. S. Letters Patent and application, the adjustment of the separation of the arc electrodes to so great a value for a given working potential that without auxiliary means for breaking down or ionizing the space or gap between the arc electrodes, the potential so applied to the arc electrodes will neither establish nor maintain the arc if once ignited by any of the well known methods. The invention also involves the employment of auxiliary means for ionizing or breaking down the arc gap and establishing and maintaining the arc at will. That is, upon the continuous application of the ionizing means the arc will at

once be ignited and maintained, and when the ionizing means is withdrawn the arc will become extinguished.

Irrespective of the particular adjustments described above it will be understood that other alternative and equivalent adjustments may be made; and that the intermittently operated auxiliary ionizing means and its control through a suitable key in conjunction with the arc, comprises the signaling system of the present invention whereby the arc current between dots and dashes, etc., is saved, and which, if desired, permits the operation of an arc on much lower voltages than has heretofore been possible owing to the arc becoming unstable.

It has been found practicable to employ an arc fed by either alternating or direct current, and with such an arc a magnetic field of either direct or alternating current may be employed. If a direct current arc is employed a direct current field should preferably be employed. In any event, however, the arc so employed is adjusted to a condition in which it will neither establish itself, nor maintain itself even after being established by any of the well known methods, and would in any case be considered as an unstable or inoperatively adjusted arc, according to the well defined principles of the present arc practice.

The condition of the arc as above described may be obtained by the adjustment of the electrodes, which may be of metal in the case of an alternating current arc; the choice of a suitable potential to be applied to the arc electrodes; and a proper strength of magnetic field, or by the relative adjustment of one of these factors with respect to the other or others.

The auxiliary means for ionizing or breaking down the arc space may be of any form of electrical discharge, disruptive or otherwise and may be energized from a separate source of current supply from that furnishing current to the arc electrodes. In this connection it should be noted that it is preferable to use the present invention in connection with alternating current arcs if large power is to be controlled because of the trouble encountered in commutating a large intermittent load on a direct current generator. Further, the metallic water cooled electrodes which may be used with an alternating current arc are particularly adapted for operation in connection with the present signaling system, as will be explained hereinafter. It is to be understood, however, that the electrodes between which the ionizing discharge is produced need not be the main arc electrodes, but may be auxiliary electrodes suitably arranged with respect to the main arc gap.

Referring now to the accompanying drawings and the following description, for a

further and more complete understanding of the invention:

Fig. 1 illustrates an alternating current arc transmitter having a direct current magnetic field and provided with auxiliary means for ionizing the arc space whereby signaling is accomplished by controlling the auxiliary ionizing means;

Fig. 2 illustrates a direct current arc transmitter provided with similar auxiliary means for signaling purposes; and

Fig. 3 illustrates an arc transmitter wherein the ionizing discharge is produced between auxiliary electrodes suitably arranged with respect to the main arc gap.

The system of Fig. 1 comprises an arc converter having main electrodes 4—5 between which an arc 1 may be maintained when once ignited and when supplied with current from the alternator 6, or other alternating current source, through the supply circuit 8—9 containing the control reactance 7. The arc 1 is subjected to the action of an electromagnetic field produced by the electromagnet 10 which is energized from the direct current 11 or other direct current source.

It will be understood that the arc 1 is so adjusted that it can neither establish itself nor maintain itself if once established. This condition may be brought about by the manipulation of the separation of the metallic electrodes, the value of the potential of the currents supplied to the arc and the strength of the magnetic field, or by the manipulation of each severally, or in combination.

The auxiliary means for ionizing the arc space between the arc electrodes 4 and 5 comprises the source of alternating current 12, the transformer 13, the gap 14 which may be any one of the well-known forms of spark gap, and the metal arc electrodes 4, 5 which are connected in the ionizing circuit at the points 15 and 16.

The operation of the system for signaling purposes is as follows: Assuming the arc to be properly adjusted and in a condition wherein it will neither establish itself nor maintain itself when once ignited, but in a condition wherein if the arc space is continuously ionized the arc will be ignited and continue to burn. The key 17 when intermittently operated to open or close the circuit 18, 19 will cause a spark discharge to occur, both in the gap 14 and across the arc space between the electrodes 4 and 5. The spark discharge between the metal arc electrodes serves to ionize the arc space and thereupon the arc will become ignited and will continue to burn as long as the spark is maintained.

It will, therefore, be seen that the key 17 serves to control the operation of the arc without controlling or interrupting large

currents and, moreover, the arc current between the dots and dashes or other characters of a word and the space between words, messages, and the like is saved.

5 The key 17 may be an ordinary sending key manually controlled by an operator, or it may be any one of the various forms of automatic keys or senders whereby high speed transmission may be practiced.

10 The system of Figure 2 is similar to that of Figure 1 with the exception that the arc 30 is supplied with direct current from the source 31 connected to the usual arc electrodes 32, 33. The arc 30 is connected in 15 the antenna-ground system 34, 35 and the auxiliary ionizing system 36, 37, 38, 39, 40, 41 is connected to the arc electrodes 32, 33 at the points 43, 44. The direct current electromagnetic field produced by the magnet 46 is energized from the direct current source 45.

20 Referring now to Figure 3 wherein the ionizing discharge is produced between the auxiliary electrodes 50-51, the arc system 25 is arranged in a similar manner to that illustrated in Figure 1. The main arc electrodes 52-53 may be of metal since the arc current is furnished from the alternator 54 or from any suitable alternating current source and supplied to the electrodes 52-53 30 through the circuit 55-56 containing the control reactance 57 for well-known purposes. As in the case of Figure 1 the arc electrodes 52-53 are direct in the antenna 35 earth system 58-59 respectively.

The circuit supplying the necessary energy for producing the ionizing discharge between the auxiliary electrodes 50-51 is arranged in a similar manner to those illustrated in Figures 1 and 2 and the auxiliary ionizing discharge is controlled by the key 60, which interrupts the alternating current supplied by the alternator 61 connected to the primary of transformer 62. The operation of the arc system of Figure 3 includes the manipulation of the key 60 in the auxiliary ionizing circuit and takes place in accordance with the explanation given in connection with the operation of the system il-

lustrated in Figure 1; that is, upon closing 50 the key 60 an ionizing discharge takes place between the electrodes 50-51 which serves to ignite and maintain the arc as long as the key 60 is closed. As soon as the key 60 is opened, however, the ionizing discharge is 55 withdrawn from the gap and the arc at once becomes extinguished. While the magnetic field produced by the electromagnet 63 supplied from the current source 64 is a direct current field, an alternating current 60 field may be employed if desired. Moreover, if the arc current supplied to the main electrodes 52-53 is obtained from a polyphase system the current employed for energizing the auxiliary ionizing means may 65 also be obtained from the same system but should preferably be connected to a different phase from that supplying the arc proper in order that the ionizing effect may be approximately a maximum when the alternating supply voltage is a minimum. This increases the antenna current considerably over that obtained when both circuits are operated from the same phase.

I claim:

1. The method of signaling with an arc transmitter which comprises igniting and extinguishing the arc by intermittently producing an auxiliary ionizing discharge in or about the arc space, maintaining the auxiliary ionizing discharge throughout the duration of each signal impulse thereby maintaining the arc throughout the duration of each of said impulses and interrupting the arc by interrupting the ionizing discharge at 85 the end of each signal impulse.

2. An arc signaling system comprising a pair of spaced arc electrodes and a source of current therefor, the spacing of said electrodes and the operating voltage being such 90 as to normally preclude igniting or maintaining an arc between said electrodes and means for reducing the resistance of the arc space whereby an arc may be intermittently established, maintained and interrupted 95 therein in accordance with signal characters.

In testimony whereof I affix my signature.
LEONARD F. FULLER.
